UNITED STATES PATENT OFFICE

160,486

LOLLIPOP STAND

Dominic Favia, Brooklyn, N. Y.

Application June 15, 1949, Serial No. 3,290

Term of patent 3½ years

(Cl. D80—10)

To all whom it may concern:

Be it known that I, Dominic Favia, a citizen of the United States, residing at 1636 Jefferson Avenue, Brooklyn, in the county of Kings, State of New York, have invented a new, original, and ornamental Design for Lollipop Stand, of which the following is a specification, reference being had to the accompanying drawing, constituting a part hereof.

Fig. 1 is an end elevational view of a lollipop stand, showing my new design.

Fig. 2 is a side elevational view.

Fig. 3 is a top plan view.

Fig. 4 is a perspective view.

I claim:

The ornamental design for a lollipop stand, substantially as shown.

DOMINIC FAVIA.
